UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

TYPOGRAPHICAL MACHINE.

1,138,003.

Specification of Letters Patent.

Patented May 4, 1915.

Application filed May 25, 1914. Serial No. 840,799.

To all whom it may concern:

Be it known that I, CARL MUEHLEISEN, a citizen of the United States of America, residing at 23 Chausseestrasse, Berlin, N. 4, 5 in the Empire of Germany, have invented new and useful Improvements in Typographical Machines, of which the following is a specification.

The present invention relates to improved 10 means for inspecting the delivery mouth of and quick changing a magazine in a multiple magazine typographical composing and distributing machine. It is advantageously applicable to multiple magazine 15 typographical composing, line-casting and distributing machines of the Mergenthaler type, commercially known under the trade mark "Linotype," when it has a single fixed distributor behind the plurality of magazines and serving them all in turn through 20 a pivoted magazine entrance, a set of escapements on each magazine, a single set of escapement rods to work any set of escapements and a single fixed assembler entrance in front of the said plurality, its 25 escapements and escapement rods.

There are known at the present time, and 30 in the machines of the type just defined, quick-changing means in which the plurality of magazines is supported upon a series of vertical cams symmetrically arranged thereunder and having their axes on a plane, parallel with that of the plurality, the so-called magazine frame upon which 35 the magazine is so supported being provided with antifriction rollers engaging with the respective cams. It is also known to provide a single magazine machine of the said type, with a hand lever by which the operator can raise the delivery mouth of that 40 magazine high enough to allow him to inspect any part of its mouth, as when the delivery of matrices from any matrix channel may have ceased, such inspection being 45 made from the front of the machine and over the assembler guide. It is also known to provide a double magazine machine of the said type with a similar lever for a like purpose, but the accomplishment of that 50 purpose is limited to the top magazine of the two, because such lever cannot raise the bottom one high enough to expose its delivery mouth to inspection.

The present invention consists in the combination with such a plurality of maga-

zines and magazine-supporting frame, of a hand lever capable of raising the delivery mouth of the lowest, and therefore of any, magazine in the plurality, high enough for any part of it to be so inspected by the operator. This capacity also provides for the front of the lowest, and therefore of any, magazine in the plurality, being raised high enough to be quick changed over the assembler entrance.

The accompanying figure is a side elevation of a preferred constructional form of the application of the invention to a machine of the type defined above. Referring to it, the plurality of magazines is represented by two, 1, 2, supported on the magazine frame 3, adapted to slide up and down in suitable guides on the machine frame as heretofore. Neither these guides nor the machine frame are included in the figure.

4 is the single fixed distributor; 5, the magazine entrance pivoted at 6 on the machine frame; 7, one of each set of escapements; 8, one of the set of escapement rods; and 9, the fixed assembler entrance.

10 is the hand lever for raising the delivery mouth of the lowest magazine in the plurality, high enough for any part of that mouth to be inspected by the operator from the front of the machine. As the assembler 85 entrance 9 is fixed in front of the delivery mouths of the magazines, it is obvious that that lowest magazine will not be high enough for such inspection until its bottom lip, *i. e.* the front edge of the bottom plate 90 of that magazine, stands at a level above, and therefore clear of, the top of the assembler entrance 9. This lever 10 has its fulcrum 11 fixed on the machine frame, and its rear end pivotally connected to the front- 95 wardly projecting arm of one or more angled links 12, having the top end of its, or tops of their, vertical arms pivotally connected, as indicated at 13, with a central point in the bottom of the frame 3 or symmetrically with that point along a transverse line passing through it. The bottom and horizontal arm of each link 12 is prolonged to the rear where it is, as indicated at 14, connected to the bottom end of a helical 100 spring 15 depending from a fixed point 16 on the machine frame, the spring being of such strength as substantially to counterbalance the weight of the magazines, so as to assist the operator in raising them. It is 110

therefore obvious that the lever 10 enables the operator to raise the delivery mouth of any—highest, lowest or any intermediate—magazine in the plurality above the top of the assembler entrance 9. It is also equally obvious that such raising puts the front of the highest, the lowest or any intermediate magazine in the plurality in position, so far as position with reference to the top of the assembler entrance 9 is concerned, for being quick-changed over that entrance.

Any of the known devices for locking the frame 3 and plurality of magazines in their adjusted position with reference to the assembler and magazine entrances 9 and 5, may be employed.

The mechanism for shifting the magazines is as follows. 17 is a cam, or one of a series of cams, and 18 is a, or one of a series 20 of cams, behind the former and fast on shafts 19, 20, journaled in the machine frame. When there are only two magazines in the plurality, as is the case in the form illustrated, each cam has only a single rise, but each additional magazine requires an additional rise, thereby making the operative edge of each cam a stepped one. Both cams or cam, series 17 and 18, are replicas of each other, both as to contour and angular position on their respective shafts.

21 is a hand lever fast on the front shaft 19 and projecting to the front of the machine within reach of the operator.

22 is a link from the front cam or cam-series 17 to the rear one 18 to make both turn together, when the lever 21 is moved. The row of escapement rods 8 is embraced by a yoke 23 movable horizontally to and fro to put the noses of the said rods out of working connection with the escapements 7 of the magazine to be changed and into working connection with those of the substituted magazine.

24 is a rearwardly extended frame carrying the yoke 23 and adapted to move it as stated, by the engagement of an eye 25 at each end on a suitably supported horizontal rod 26. The frame 24 is moved by the front cam or cam-series 17, and to enable them to do that each is duplex inasmuch as it has a special rise 27 for that purpose. As soon as the lever 21 is started, a rise 27 rocks the top end of a lever 28 fulcrumed on a stationary fulcrum 29 and in constant engagement with that rise, to the rear, thereby making the bottom arm of the lever 28 push the frame 24 to the front, thereby disengaging the rods 8 from the escapements 7 of the magazine to be changed. This disengagement is accompanied by the rocking back of the magazine entrance 5 on its pivot 6, which rocking back is effected by an arm 30 fast on the fulcrum 29, a second arm 31 fast on the pivot 6, and a link 32 connecting their outer ends.

65 33 is an adjustable connection between the

frame 24 and the bottom end of the lever 28. There are notches 34 in the rise 27 so positioned therein that one of them engages the top end of the lever 28 whenever the escapement rods 8 are in working connection with a row of escapements 7, and to lock them there.

The reversal of the lever starts the magazine frame 3 and as soon as the substituted magazine is in composing position, the magazine entrance 5 and the escapement rods 8 are returned to their working position and the former locked there.

Having described my invention, I declare that what I claim and desire to secure by Letters Patent is:—

1. In a typographical machine, the combination of a plurality of magazines, a frame carrying the magazines, means for shifting the frame to bring one or another of the magazines into operative position, and further means for moving the frame and all of the magazines thereon as a whole from their shifted position to facilitate the removal of the magazines.

2. In a typographical machine, the combination of a plurality of magazines, a frame carrying the magazines, means for shifting the frame to bring one or another of the magazines into operative position, and further means for moving the frame from its shifted position to facilitate the removal of the magazines, the said means comprising a hand lever fulcrumed in the machine frame and connections between said lever and the magazine frame.

3. In a typographical machine, the combination of a plurality of magazines, a frame carrying the magazines, means for shifting the frame to bring one or another of the magazines into operative position, and further means for moving the frame from its shifted position to facilitate the removal of the magazines, the said means comprising a hand lever fulcrumed in the machine frame and an angled link pivotally connected to the hand lever and the machine frame respectively.

4. In a typographical machine, the combination of a fixed assembler entrance, a plurality of magazines, means for moving the magazines vertically to bring one or another into operative relation to the assembler entrance, and means distinct from the magazine moving means for lifting the magazines as a whole above the level of the assembler entrance for removal or inspection.

5. In a typographical machine, the combination of a fixed assembler entrance, a plurality of magazines, means for moving the magazines vertically to bring one or another into operative relation to the assembler entrance, means distinct from the magazine moving means for lifting the

magazines as a whole above the level of the assembler entrance for removal or inspection, and counterbalancing devices connected to said lifting means.

5 6. In a typographical machine, the combination of a fixed assembler entrance, a plurality of magazines, means for moving the magazines vertically to bring one or another into operative relation to the as-

10 sembler entrance, means distinct from the magazine moving means for lifting the magazines as a whole above the level of the assembler entrance for removal or inspection, and counterbalancing means to assist in

15 the lifting of the magazines.

7. In a typographical machine, the combination of a fixed assembler entrance, a plurality of magazines, means for moving the magazines vertically to bring one or another into operative relation to the assembler entrance, means distinct from the magazine moving means for lifting the magazines as a whole above the level of the assembler entrance for removal or inspection, and means for counterbalancing the weight of the magazines when subject to the action of either of the two before-mentioned means.

8. In a typographical machine, the combination of a plurality of magazines movable as a whole to bring one or another into operative position, means for effecting such movement of the magazines, and means independent of such moving means for shift-

ing the magazines as a whole from their 35 moved position to facilitate their removal.

9. In a typographical machine, the combination of a plurality of magazines, a series of cams for moving the magazines vertically to bring one or another into operative position, and means for raising the magazines to an extent beyond that controlled by the cams.

10. In a typographical machine, the combination of a plurality of magazines movable vertically as a whole to bring one or another into operative position, means for effecting such movement, and independent means for moving the magazines as a whole to an extent beyond that controlled by the 50 first means.

11. In a typographical machine, the combination of a fixed assembler entrance, a plurality of magazines, means for shifting the magazines vertically to bring one or another into operative relation to the assembler entrance, and means for moving the magazines as a whole relatively to their shifting means to locate the lowermost magazine above the level of the assembler entrance 60 for removal or inspection.

In witness whereof I have hereunto set my hand in the presence of two witnesses.

CARL MUEHLEISEN.
